US00D362826S

United States Patent [19]

Weder et al.

[11] **Patent Number:** **Des. 362,826**[45] **Date of Patent:** ****Oct. 3, 1995**[54] **FLOWER POT COVER**

[75] Inventors: **Donald E. Weder; Joseph G. Straeter**, both of Highland, Ill.

[73] Assignee: **Highland Supply Corporation**, Highland, Ill.

[**] Term: **14 Years**

[21] Appl. No.: **808,567**

[22] Filed: **Dec. 16, 1991**

Related U.S. Application Data

[63] Continuation-in-part of Ser. No. 710,272, Jun. 4, 1991, which is a continuation-in-part of Ser. No. 617,454, Nov. 21, 1990, abandoned, and a continuation-in-part of Ser. No. 411,249, Sep. 22, 1989, and a continuation-in-part of Ser. No. 411,247, Sep. 22, 1989, and a continuation-in-part of Ser. No. 411,245, Sep. 22, 1989.

CLAIM

The ornamental design for a flower pot cover, as shown and described.

DESCRIPTION

FIG. 1 is a perspective view of our new flower pot cover design;

FIG. 2 is a side elevational view thereof;

FIG. 3 is a top plan view thereof;

FIG. 4 is a bottom plan view thereof;

FIG. 5 is a side elevational view of the design of FIG. 1, the only difference being the angle of the skirt;

FIG. 6 is a side elevational view of the design of FIG. 1, the only difference being the angle of the skirt;

FIG. 7 is a top plan view of a second embodiment of the design of FIG. 1, the only difference being the size of the skirt;

FIG. 8 is a top plan view of a third embodiment of the design of FIG. 1, the only difference being the size of the skirt;

FIG. 9 is a side elevational view of a fourth embodiment of the design of FIG. 1, the only difference being the height; and,

FIG. 10 is a side elevational view of a fifth embodiment of the design of FIG. 1, the only difference being the height. The flower pot cover has no substantial thickness.
